UNITED STATES PATENT OFFICE

ELMER D. BARRINGER, OF CLEVELAND, OHIO

WEATHER STRIP

Application filed March 24, 1930. Serial No. 438,557.

My invention relates to weather strips and more particularly to metal weather strips for use in conjunction with casement windows, doors, and the like, for sealing the space between the same and the supporting frame to make a weather tight connection therebetween and to effectively prevent any water or air from passing through the opening between the frame and the sash when the latter is in closed position.

An object of my invention is to provide a weather strip having vertically disposed cooperating resilient water sealing elements, the sealing joint of which is disposed in a substantially horizontal plane, and a cooperating resilient air sealing tongue disposed between the window and the sill, all of said elements being easily and conveniently applied from the exterior of the window and sill structure.

Another object of my invention is to provide fastening or securing means for the cooperating elements of the weather strip which constitute adjusting means for the sealing elements whereby the cooperation between the parts may be quickly and easily adjusted when so desired.

A further object of my invention is to provide draining instrumentalities for the water sealing means which are associated with the weather strip to permit the securing means and the adjusting means to be inserted or adjusted therethrough.

A still further object of my invention is to provide a weather strip which is entirely applicable to casement windows from one side thereof, certain of said securing means constituting adjusting means therefor.

Other and further objects and advantages of the invention will be hereinafter set forth and the novel features thereof defined by the appended claims.

In the drawings:

Fig. 1 is a perspective view of a preferred form of my improved weather strip as ap-

plied to a window, showing the parts in co-operating sealing position.

Fig. 2 is a fragmentary elevation of a portion of a slight modified form of weather strip.

Fig. 3 is a detail sectional view taken on line 3—3 of Fig. 2.

Fig. 4 is a fragmentary elevation of a further modification of my weather strip.

Fig. 5 is a sectional view on the line 5—5 of Fig. 4.

Fig. 6 is a detail perspective view of a portion of the lower adjustable weather strip element as seen in section in Fig. 5.

Like reference characters refer to like parts in the several figures of the drawings in which A represents a casement window which is movable into and out of operative relation with the sill or frame B, the direction of movement of the window being indicated by the arrow A'. An angularly bent deflecting member 1 is secured to the window in any suitable manner, such as by screw fastening means 2. The deflecting member 1 projects outwardly and downwardly from the securing flange 1a and is then rebent inwardly in a substantially horizontal plane and again bent outwardly to form the receiving channel 3 for the cooperating tongue 11 carried by the lower adjustable weather strip member 4.

The lower cooperating member 4 is also of channel formation and consists of a vertically disposed securing flange 5 adapted to lie against the frame of the window B and a correspondingly substantially vertically disposed spaced portion 6 which terminates in a laterally positioned engaging flange 11. This flange 11 is designed and arranged to cooperate with and engage the base of the receiving channel 3 when the window is in closed position, as seen in Fig. 1.

Disposed directly behind the longitudinal channel 3 and secured to the face of the window A, is a sealing tongue 8. This sealing

tongue is of resilient sheet metal construction and designed to engage the frame B of the window casing when the window is closed to effectively prevent the passage of air or moisture between the window and its casing or frame.

10 The channel portion of the upper deflecting member 1 engages the securing flange of the sealing tongue member 8 which acts as a supplemental means for holding the tongue in operative position in addition to the securing means 9 therefor. The lower cooperating member 4 is secured to the frame B of the window by suitable fastenings such as the screws 10, and it will be observed that by proper adjustment of these screws the engaging flange or tongue 11 may be properly positioned with respect to the receiving channel 3 carried by the upper deflecting member 1. In order to prevent water which may pass around the cooperating tongue and channel members 11 and 3 from collecting in the lower channel 8, weep holes or openings 12 are provided in the base of the channel 4.

20 Referring to the form illustrated in Figs. 2 and 3, it should be noted that the vertically disposed securing flange 5' is slightly bowed or curved, as at 13, and the fastening screws 14 engage this flange directly rather than by engaging the opposing free flange, as seen in the form disclosed in Fig. 1. Apertures 15 are provided in the free flange for inserting the screw securing means 14 therethrough and permitting an instrument to be inserted through the apertures to increase the tension on the bowed portion 13 of the flange 5 to adjust the position of the tongue member 11. In this form of the invention the apertures 15 also constitute weep openings for discharging any water which may collect in the base of the channel member 4.

25 Referring to Figures 4, 5 and 6, which disclose a slightly different form of combined securing and adjusting means and weep openings in which the lower cooperating member 4a is slit as at 16, the intermediate portions between the slits are pressed inwardly to lie substantially adjacent to and slightly spaced from the vertically disposed flange 5a, as indicated at 17 in Fig. 5. The spaces between the bent-in portions of the body of the channel constitute weep openings 18 for discharging any moisture which might collect in the channel. Since the lower cooperating member 4a, as disclosed in this figure, is of resilient material, the adjustment of the screw securing means 19 will move the cooperating tongue 11a toward or away from the channel 3a of the upper deflecting member 1a.

30 While the modified views of this construction, as shown in Figs. 2 to 6, are more or less fragmentary and do not disclose the supplemental resilient sealing tongue 8, it is, of course, contemplated to use this supplemental member in conjunction with these forms of

the invention as well as the preferred embodiment, as seen in Fig. 1.

35 In describing the general operation of the device, it should be noted that with the window in closed position, as seen in Fig. 1, rain sleet, etc., striking the upper deflecting member 1 will be deflected outwardly and away from the lower cooperating member 4. Since this member is disposed slightly inside the projecting edge of the deflecting member 1, any moisture which may leak past the end of the tongue 3 and find its way into the channel of the lower member 4, will leak out through the weep openings 12 of Fig. 1, or the openings 15 of Fig. 3, or in the case of Fig. 5, through the openings formed by the slits 16. By adjustment of the securing means, the engaging flange 11 may be brought into proper cooperation with the channel 3 to reduce this leakage to a minimum. The supplemental resilient tongue member disposed on the casement window just behind the channel 3 and engaging the frame or sill B will effectively prevent moisture or air from leaking through the space between the window and the frame thereof.

40 It will be therefore seen that this present improved construction has the inherent advantage of being applicable to a window without requiring the necessity of any work being done on the window itself to permit the installation of the present strip. This in itself marks a very practical advance over prior strips of this general type, the installation of which prior strips have, so far as is known, inevitably required a portion of the window itself to be cut away in order to obtain a satisfactory fitting of the strip.

45 While the specific details of construction have been herein shown and described, the invention is not confined thereto as changes and alterations may be made without departing from the spirit thereof as defined by the appended claims.

50 Having thus described my invention, what I claim as new and desire to secure by Letters Patent is:

55 1. In a weather strip, an upper member adapted to be secured to the outside of a window, said member having a channel, a cooperating lower member secured to the outside of a window frame, securing means for said lower member, said securing means constituting adjusting means for adjusting the lower member with respect to the upper member, and a supplemental sealing member disposed between the window and frame when the same is closed and cooperating with the channel of said upper member.

60 2. In a weather strip, an upper member adapted to be secured to the outside of a window and bent to form inwardly and outwardly disposed horizontal channels, a lower horizontal channel member having an upstanding base portion secured to the outside of a window.

dow frame, the said member being bent first downwardly and then upwardly to form a channel of substantially **U**-shaped configuration, the side of the **U** opposite the base portion extending upwardly beyond the base portion and then being bent inwardly to form a tongue fitting into the outwardly disposed channel of the upper member, and securing means for the lower channel member extending into the interior thereof, the securing means also providing adjustment of the position of the tongue within its engaging member.

3. In a weather strip, an upper member adapted to be secured to the outside of a window and bent to form inwardly and outwardly disposed horizontal channels, a lower horizontal channel member secured to the outside of a window frame, the said member comprising a base portion flatly engaging the window frame, the upper side of the lower channel member forming a tongue fitting into the outwardly disposed channel of the upper member, and securing means for the lower channel member projecting therethrough, the upper side of the lower member having areas adjacent the securing members slotted and pressed inwardly, the securing members thereby also providing means for adjusting the position of the tongue within its engaging member.

4. In a weather strip, an upper member adapted to be secured to the outside of the window and bent to form outwardly and inwardly disposed horizontal channels, a lower horizontal channel member cooperating with the upper member and secured to a window frame, the lower channel member comprising a substantially **U** shaped channel, one side of which forms a vertically disposed sill engaging portion, the other side of the channel extending upwardly and terminating in a tongue fitting into the outwardly disposed channel of the upper member, and securing means for the lower channel member applied directly to the sill engaging portion, the other side of the lower **U** channel being provided with apertures aligned with the securing means to permit insertion of an instrument therethrough for manipulation of the securing means and to serve as weep holes for discharging any water which may collect in the base of the channel member.

5. In a weather strip, an upper member adapted to be secured to the outside of the window and bent to form outwardly and inwardly disposed horizontal channels, a lower horizontal channel member cooperating with the upper member and secured to a window frame, the lower channel member comprising substantially an upstanding **U**-shaped channel, one side of which forms a vertically disposed sill engaging portion, this portion being slightly bowed, the other side of the channel extending upwardly and terminating in

a resilient tongue fitting into the outwardly disposed channel of the upper member, and securing means for the lower channel member applied directly to the bowed sill engaging portion, the other side of the lower **U** channel being provided with apertures permitting insertion of an instrument therethrough to effect manipulation of the securing means to thereby adjust the position of the resilient tongue relatively to its channel.

In testimony whereof I affix my signature.
ELMER D. BARRINGER.
